GUN AIMING SYSTEM

René Battaglini, San Francisco, Calif.

Application May 2, 1946, Serial No. 666,777

28 Claims. (Cl. 89—41)

(Granted under the act of March 3, 1883, as
amended April 30, 1928; 370 O. G. 757)

1

The invention described herein may be manufactured and used by or for the Government for governmental purposes, without the payment to me of any royalty thereon.

In certain types of antiaircraft guns now in use, the gun is moved angularly by hydraulic motors, one for elevation and another for train. Each motor is controlled by a light pilot valve which, in turn, controls a main valve. The pilot valve is of the reciprocating piston type and the connections are such that when the valve is in central position, a source of high pressure fluid is cut off from the motor so that no movement of the gun occurs. When the pilot valve is displaced in one direction, pressure fluid is thereby admitted to a corresponding end of the main valve which being displaced thereby, permits pressure fluid to flow to one side of the corresponding hydraulic motor to angularly move the gun in a first direction while, when the pilot valve is displaced in the other direction, the motor is operated to drive the gun in a second or opposite direction.

In the types of guns under discussion, control of the pilot valve is usually effected from a separate or distant director through electric telemetric connections of the "Selsyn" type. Certain values such as range, present position, elevation and azimuth rates of the target, are introduced into the director. The director then combines these values and delivers an output consisting of two continuously-changing angular values. These values are the predicted azimuth angle and elevation angle that the gun should have in order to hit the target if fired at that particular instant. Each value is separately transmitted to the gun by a "Selsyn" transmitter having its field coils connected by standard Y or delta three-phase connections to the stator of a differential repeater. The rotor of the aforesaid repeater has standard three-phase connections with the stator of a gun transmitter whose rotor is geared to rotate in timed relation with the elevation or train motor of the gun, as the case may be. The rotor of the differential repeater is mechanically connected to a torque arm operating the aforesaid pilot valve. Thus, as the rotor of the transmitter at the director is turned through an angular increment the field induced thereby in the stator of the gun transmitter rotates through the same increment and the three-phase connections cause an equal rotation of the field induced by the stator coils of the differential. As the field induced by the rotor coils of the differential repeater is momentarily at rest

2

because of the fact that the hydraulic motor is not rotating, there is an increment of relative rotation between the stator and rotor fields of the differential. This relative rotation causes a torque to be applied to the torque arm and results in a shift of the pilot valve. The connections are such that the ensuing rotation of the hydraulic motor causes a corresponding increment of rotation of the stator field of the gun transmitter to restore parallelism between the fields of the stator and rotor of the differential repeater. The movement is smooth and continuous, with substantially no lag, so that the gun at all times repeats or follows up the corresponding angular output of the director; and it will be noted that the rate of angular movement of the gun corresponds, in each case to the angular displacement of the stator and rotor fields of the differential repeater and, hence, to the angle of displacement of the aforesaid arm.

At times it is preferable or necessary, as when firing at relatively close range, or when the director has been put out of action by enemy fire, to control the gun manually, effecting aim solely by observation of the tracers. Manual control is also desirable when it is desired to rapidly move the gun to direct the same in the general direction of a fast-moving target, preliminary to switching to director control. To accomplish these purposes, I propose to provide a control element which may be carried directly upon the gun mount or spaced an appreciable distance therefrom, together with a clutch by which said control element may, through Bowden cables, be connected to directly control the aforementioned torque arm. By this construction, the gun may be controlled by and from the director, when desired, or may be substantially instantaneously converted to manual control when dictated by the conditions or exigencies of combat.

It is accordingly an object of the invention to provide an attachment for automatically controlled guns that may be substantially instantaneously substituted for director control and which may, with equal facility, be disconnected when it is desired to return to automatic or director control.

Another object is to provide an attachment as aforesaid that affords a positive mechanical linkage or connection from a central control point to the pilot control valves previously mentioned.

Another object is to provide a manual control for the power drives of guns that may be actuated from a central station by one operator and that affords a precise, accurate control operable in a

natural manner to enable the gun to be moved smoothly and at a desired rate to a position indicated by the tracers or bursts as necessary to effect a hit.

A still further object is to provide a manually operable central station control that is readily adjustable at the gun for the most convenient operating position, while, effecting control by a single element movable about mutually perpendicular axes.

Another object is to provide in a single unit, elevation and train controls for a gun and in which the movements necessary to effect the desired component angular movements of the gun, in train and elevation bear a natural relation to the respective components so that the operator has the sensation that he is directly moving the gun. In this way, rapid sensory response of the operator to imperfect aim is assured and vertigo on the part of the operator is avoided.

A further object is to provide a manual control system, as aforesaid, that may be attached to existing types of guns, for which it is intended, quickly and, without, in any way hampering the original intended manner of operation of the gun, when desired.

A still further object is to provide a manual control system for use by a single operator using forward area sights or tracer control to track the target smoothly and rapidly.

Other objects and advantages of the invention will become apparent as the description proceeds.

General description

In general, the invention comprises a steering wheel or disc mounted upon the portion of the gun support that is pivoted to move the gun about a vertical axis. The steering wheel is located at one side of, and closely adjacent the gun so that the operator, in effect, looks along the bore of the gun and is in position closely to observe the trajectories of the tracers. The wheel itself is mounted upon a bracket for movement about a first axis substantially parallel to the trunnion

or elevation axis of the gun and a second axis normal to the first axis and centrally of the wheel. Disconnectable flexible connections are provided between the respective axes of the wheel and the oil gears whereby movements of the wheel about the first axis causes elevational or depression movements of the gun in the same direction. That is for example, if the wheel or disc is tilted upwardly, the gun is elevated. Also rotation of the wheel about the aforesaid second axis moves the gun in train. Again the direction of train is made the same as the direction of rotation of the wheel. In all cases, the rate of movement of the gun is proportional to the angular displacement from null or zero positions of the wheel about its respective axes. By the arrangement described, the operator or gunner intuitively moves his wheel in the proper direction necessary to correspondingly displace the trajectory of the projectiles as indicated by tracers so that it intersects the target. By manually-operated clutch connections, the steering wheel control may be quickly connected and disconnected so that shift from director to manual control or vice versa, may be effected rapidly, as called for by changing conditions of combat.

The oil gear control

For the purpose of aiding an understanding of the invention, it will be assumed that the oil gear shown schematically at Figure 1, controls the movement of the gun in azimuth. It will be understood that a similar system is provided in each gun, for controlling the movement thereof in elevation.

A transmitter 1 is located at a gun fire director remote from the gun emplacement, and includes a rotor coil 2 and delta-connected stator coils 3. A cable including conductors 4 connects the respective terminals of the stator coils 3, with the corresponding terminals of stator coils 5 of a differential repeater 6 having a rotor including delta-connected coils 7. A shaft 8 is connected to be turned by rotation of the rotor of differential repeater 6. This shaft has an arm 9 fixed thereto which, through a link 10 may move the piston 11 of a fluid pressure control valve 12 within its cylinder 13. Fluid such as oil, under pressure, is supplied by way of a central connection 14 to the interior space defined by the separated sections of piston 11. Outlets 15 and 16 extend from cylinder 13 to a hydraulic motor 17 having its shaft 19 connected, in this particular case, to turn the gun in azimuth. The motor 17 also has its shaft connected as at 20, to the rotor 21 of a gun transmitter 22 whose stator coils 23 are delta-connected by conductors 24 to the coils of rotor 7 of differential repeater 6.

In normal or neutral position, both outlets 15 and 16 are blocked by piston 11 and motor 17 is at rest. When a change in predicted azimuth is developed in the director a corresponding rotation of coil 2 is effected. This results in a rotation of the field induced in coils 3 by rotor 2, and a corresponding rotation of the field induced by the stator coils of differential repeater 6.

The rotor coil 21 of gun transmitter 22, acts to induce a field in its stator coils 23 and this field is repeated by rotor coils 7 of differential repeater 6. When, therefore, the field induced by coils 5 rotates relatively to the field of coils 7, a torque is applied to shaft 8 which effects a movement of piston 11 against the action of centralizing springs 25 and in a direction depending upon the direction of rotation of rotor 2. Move-

ment of piston 11 admits fluid under pressure to one outlet and permits exhaust from the other. As a result, motor 17 turns and the mechanical connections are such as to turn the gun in the direction corresponding to the direction of rotation of rotor 2 and also to turn rotor 21 of gun transmitter 22. A rotation of the field of coils 7 is thereby effected and the connections are such that this field rotation follows the field rotation of coils 5. As soon as the field of coils 7 is again in agreement with the field of coils 5, the torque on arm 9 disappears, springs 25 return piston 11 to central or neutral position, and motor 17 stops.

The action just described is smooth and continuous so that the gun rotates in the direction corresponding to the rotation of coil 2, substantially without lag. It should also be noted that the rate of angular movement of the gun will be proportional to the displacement from central position of piston 11. The foregoing system is duplicated in each gun for elevation control, the only difference being that shaft 19 is connected to operate the elevating gears of the gun, and rotor coil 2 in the director is driven in accordance with the predicted elevation angle to be applied to the gun.

It will be understood that motor 17 drives both the gun and coil 21 through reduction gearing, not shown in Figure 1. Figure 2 shows the oil gear as actually used in a standard 40 mm. anti-aircraft unit. In this figure, the parts are enclosed within a casing 26 connected with brackets 27 and 28 of the induction motor that drives the oil pump. This casing is normally closed by a cover plate which has been removed in Figure 2. The differential repeater is indicated at 6 and its rotor shaft 29 carries a torque arm 30 having a projection 30a extending from one side. This carries an adjusting screw 31 operable to vary the connection between 30a and pilot valve piston 11 slidable within cylinder 13. A second projection 30b extends from the left side of torque arm 30, as seen in Figure 2, and carries an actuating pin 33 having its axis parallel to the axis of shaft 29. Centralizing springs 25 are secured at their adjacent ends to projection 30b, and at their remote ends to the casing of repeater 6. The gun transmitter 22 is located within the casing 26 at the left, as seen in Figure 2. The shaft 34 of transmitter 22 is connected with spiral gear 35 by an adjustable coupling so that slight relative rotation between the two may be effected after loosening screws 36. Gear 35 is in mesh with a spiral pinion 37 fixed on a shaft 38 journaled in bearings, one of which is mounted in a bracket 39. This bracket is held in place by screws 40. Shaft 38 is connected through appropriate reduction gears with the gun azimuth hydraulic motor in the case of the azimuth oil gear, and with the gun elevation hydraulic motor in the case of the elevation oil gear. From the explanation presented in connection with Figure 1, it will be clear that when a relative rotation of the fields induced in stator and rotor coils 5 and 7 of repeater 6, a torque is applied to shaft 29 that effects a displacement of piston 11 in one direction or the other, to thereby initiate a corresponding rotation of the azimuth or elevation motor, as the case may be. This displacement is effected against the action of springs 25. The resulting operation of the hydraulic motor drives shaft 38 and gear 35 to cause the induced field of differential repeater rotor 7 to follow the rotation of stator field 5 and restore alignment between the two fields. When this has been effected

the torque on shaft 29 disappears and springs 25 return piston 11 to neutral, thus stopping the motor.

The features just described are well known and form no part of my invention. It will be noted that with oil pressure on and the circuit of conductors 4 open, control of the gun is possible by manually applying torque to the arms 30 of the respective azimuth and elevation oil gears. My invention includes means for doing this by applying forces to pins 33.

Figure 3 shows the azimuth oil gear of Figure 2 with the adapter means of the invention applied thereto. U-shaped upper and lower spacers 44 and 45 are provided to extend part way around the flange of casing 26. At the left side of Figure 3, the edges of these spacers are indicated at 44a and 45a, respectively, so that, when the adjacent section 55 of the cover plate is in position, a slot is formed through which control cables 46 and 47 may pass to the interior of the oil gear casing 26. At the right of Figure 3, these spacers have spaced edges 44b and 45b so that when cover plate section 55 is in place, a slot is formed through which clutch plate 48 may slide.

As shown in Figures 3 and 7a, a bracket plate 49 extends vertically across the central portion of the casing and is adapted to be rigidly secured thereto by central studs 42. The side edges of plate 49 are offset or raised to accommodate the adjacent center edges of cover plate sections 55 and 56. Thus, each section can be removed upon removal of the corresponding end pair of nuts 43. A guide block 50 has a width to smoothly fit between the sides of a longitudinal slot 51 in slide 48, and is of a thickness slightly greater than the thickness of said slide. A stop plate 52, Figure 4, has tapped holes 53 adapted to be engaged by a pair of cap screws 54 passing inwardly through aligned holes in plate 49. Plate 52 overlaps the edges of slot 51 and thus coacts with block 50 to confine the movement of clutch plate 48 to longitudinal translation. A locking pin 57 is slidably mounted in a hole in plate 49 (Figure 6), and is urged inwardly by a spring 58 acting between the head of said pin and an abutment 59 secured to plate 49. The end of the pin is adapted to fit either of a pair of holes 60 in slide 48 and thus releasably secure the slide in either of two positions. The significance of these positions will be subsequently described.

Slide 48 has a reduced end 48a carrying a pin 61 exteriorly of casing 26, and by which the plate 48 may be shifted from one position to the other after retraction of locking pin 57. At the other end of slide 48 there is a bracket 62 attached by screws 63 and having an outstanding portion provided with slots 64 and 65, shown at Figure 5. As clearly shown at Figures 3 and 4, these slots are adapted to receive the sheathing of flexible cables 46 and 47 so that when nut 66 is turned down on a headed sleeve 67 on cable 46, for example, the sheathing is clamped to the bracket. The clamping construction is the same for both cables. Various openings such as 69, 70 and 11 are provided in slide 48 for the purpose of facilitating adjustment of screws, etc., located behind said slide.

A torque arm actuating lever 68 is shown at Figures 3 to 8, inclusive. This lever comprises a main central portion 73 from which arms 72 and 74 extend in opposite directions. These arms have respective longitudinal slots 75 and 76. In addition, parallel arms 77 and 78 extend from

central portion 73. Each said arm is L-shaped in cross-section with vertical flanges extending toward each other as best shown upon Figure 7. A pivot hole 79 extends centrally of lever 68, through portion 73 and, as shown in Figure 4, a pivot screw 80 engages a tapped hole 81 in slide 48 to thereby pivotally mount lever 68 on slide 48. From Figures 3, 4 and 8, it will be noted that arms 77 and 78 carry leaf springs 82 and 83, respectively. Each spring is bent back upon itself to form legs of unequal length. The shorter leg is flat and has a hole through which securing and adjusting screws 84 and 85 pass to attach each spring to its respective arm 77 or 78 by means of nuts 86 to 89, inclusive. The longer legs of springs 82 and 83 are bowed toward each other, as best shown in Figure 8, whereby they may receive pin 33 between them. Furthermore, by turning screws 84 and 85 inwardly, the ends thereof may be made to engage the bowed portions of springs 82 and 83 and thus adjust the force with which each spring engages the pin, while, at the same time effecting, if desired, a slight angular movement of lever 68 relatively to pin 33. Figures 3 and 8 show the position of these springs when slide 48 is moved inwardly to cause them to engage pin 33, while Figure 4 shows their position when said slide is moved outwardly to disconnect them from the pin.

The core wire 90 of cable 46 has a hook 91 secured to its end within casing 26. This hook engages over a smooth part of the shank of a bolt 92. The threaded outer part of said shank passes through slot 75 and is clamped in adjusted position along said slot by nuts 93 threaded thereon and engaging opposite sides of the lever. By loosening one of these nuts the bolt 92 may be slid along slot 75 to vary the radial distance of the axis of said bolt from the pivot screw 80. The core 94 of cable 47 is connected in a like manner, through hook 95, with the lower end of lever 68. A detailed description is unnecessary since the two connections are identical. As shown at Figure 4, each core is beaded at its end, as shown, at 96 for core 90. In this manner, each cable may be connected with its hook simply by slipping the core through the slotted offset end of the hook. See Figure 6.

The operation of this portion of invention will be clear from the foregoing description. When slides 48 of both elevation and azimuth oil gears, are in their outward or released position, springs 82 and 83 are entirely out of contact with pins 33 and the gun may be automatically controlled from the director, in the usual manner. When it is desired to manually control the power drives, the various circuits are opened, pins 57 are withdrawn, and each slide 48 is moved inwardly and locked, in the position shown in Figure 3. Springs 82 and 83 are now in firm but yielding engagement with pin 33 and any movement imparted to cores 90 and 94, will effect a pivotal movement of lever 68, a corresponding rotation of torque arm 30, and translation of pilot valve piston 11. Thus it is possible to shift instantly from automatic director to manual control, and vice versa. It will be noted that when slide 48 is in effective or operating position as shown in Figure 3, the pivots of lever 68 and torque arm 30 are in substantial alignment.

It is within the purview of the invention to provide mechanical or electrical operating means for effecting shift of slide 48 from a remote control station. Thus pin 57 might be withdrawn by energization of a corresponding one of a pair of

solenoids connected to slide 48 directly or through appropriate bellcranks. Then energization of the solenoids at the remote control station in the proper sequence, will permit rapid shift between the two types of control just mentioned. Alternatively flexible cable controls may be run from pin 57 and slide 48 to the aforesaid remote control station for a like purpose.

The manual operating unit

In general, the manual operating unit comprises a so-called "steering wheel" rotatable about two mutually-perpendicular axes, a first of which is central of, and normal to the plane of said wheel, and a second of which is parallel to a diameter of said wheel. The wheel is so connected that movement thereof about the first axis operates the azimuth control cables while movement about the second axis operates the elevation control cables.

Referring more particularly to Figures 9 and 10, 100 identifies the left trunnion support of the gun carrying a bearing 101 within which is journaled a trunnion extending from the breech casting assembly 102. Although they form no part of the present invention, it may assist in understanding the invention to identify breech operating lever 103, right and left frames 104, 105 and rear guide 106, of the automatic loader, side cover plate 107, elevating arc gear sector 108, equilibrators 109, firing plunger 97 and firing lever 98. It should also be noted that upper and lower elevation stops 192 and 193 are provided on sector 108 to engage a part on the trunnion support and thus limit elevation and depression of the gun. Figures 9 and 10 show portions of the elevating mechanism located upon the left-hand side of the gun including a hollow post 110 rising from the top carriage frame and containing a shaft adapted to be driven from bevel gearing within a gear housing 111. A stub shaft 112 is connected to drive these bevel gears and has a squared end portion adapted to receive a crank when the gun is to be directly manually elevated by an operator seated in chair 113.

A clamp 114 is formed in two sections, pivotally connected by bolt 115, Figure 9. This clamp extends about post 110 and is drawn firmly about said post by turning a nut 116 to draw the two halves of the clamp together. One section of the clamp is forked as at 117, for quick removal. The other section is extended to form a base for a right angular support bar 119 presenting a flat upper surface from which a pair of spaced lugs 120 and 121 extend upwardly. These lugs have aligned holes to receive a pair of clamp bolts 122 and 123, respectively.

A pair of slides 124 and 125 are formed of appropriate lengths of angle iron and have their upstanding flanges slotted as shown upon Figure 10, and their horizontal flanges in the plane of the upper surface of bar 119. The bolts 122 and 123 pass through the respective slots in slides 124 and 125 as well as lugs 120 and 121, so that, when the nuts on said bolts are loosened, the slides, as well as the entire control wheel structure supported thereby, may be adjusted forwardly or backwardly to suit the operator. After adjustment, the nuts are tightened to rigidly clamp the slides in position on bar 119. A brace bar 126 is secured at its forward end to a bracket 127, Figure 10, by a clamp bolt and nut indicated generally by numeral 128. Bracket 127 is bolted to a convenient part of the top carriage of the gun, that is, the main support of the gun pivotally

movable about a vertical axis to train the gun in azimuth. The other end of bar 126 is clamped by a bolt 129 to bar 119, at a point substantially midway between lugs 120 and 121. This bar therefore acts to rigidly brace the control wheel assembly relatively to the gun and to prevent vibration thereof during firing.

As shown upon Figures 10 and 13, the slots in slides 124 and 125 terminate short of the rear 10 end of their flanges which are there provided with bearing holes. A control wheel supporting frame is indicated generally by the numeral 130. This frame, as shown, is built up from a pair of short strap sections 131 and 132, Figures 11 and 12, 15 held in parallel coextensive relation by a U-shaped connector bar 133. The sides of the connector bar are secured to strap sections 131 and 132 by bolts to form a rigid frame. The lower end of sections 131 and 132 have apertures 20 in alignment with the aforesaid bearing holes in the ends of slides 124 and 125. Bolts 135 and 136 pass through these aligned holes and act as pivot pins to enable adjustment of the frame 130 about a normally horizontal axis parallel to the 25 steering wheel. Frame 130 and parts carried are secured in adjusted position about this axis merely by tightening the nuts on bolts 135 and 136. The steering wheel assembly is thus mounted for both vertical and forward and backward translation, as well as for pivotal adjustment about a transverse normally horizontal axis.

The upper ends of strap sections 131 and 132 have aligned holes forming a normally horizontal pivot axis for a hollow shaft 137 which, 30 as shown more clearly in Figures 11 and 12, is cut away at 138 along a plane through the axis thereof over a portion that includes the axle 138 of wheel 139. It will be noted that connector bar 133 is provided at its right end, as seen upon 35 Figure 12, with a pair of split bushings 140 and 141 which, when the nuts carried thereby are turned down, are adapted to clamp the sheathing of flexible cables 46' and 47' to said bar.

The cores of said cables extend in opposite 40 directions, for a full turn about hollow shaft 137 and are there clamped beneath the respective heads of bolts 142 and 143 extending diametrically through section 137. In this manner, as shaft 137 is rotated on its axis, cables 46' and 50 47' act to transmit the motion to the elevation torque arm actuating lever. Thus, when the clutch plate or slide carrying this lever is in active position, rotation of tube or shaft 137, as aforesaid, initiates and controls elevation movement of the gun. Referring to Figure 10, the connections are such that when shaft 137 is rotated clockwise, the gun is elevated while, when 55 said section is rotated counterclockwise, the gun is depressed. It should be mentioned that very light flexible cables are sufficient to transmit the necessary forces. This cable may conveniently be of the size commonly used in connection with the carburetor choke controls of automobiles.

A circular base plate 144 is rigidly secured to 60 shaft 137. This may conveniently be done by a special bracket 146 which, as seen in Figure 12a, comprises generally a U-shaped member 153 having aligned holes 147 and 148 to snugly receive shaft 137. Parallel angle sections 149 and 150 are bolted to the U-shaped member so that their upper surfaces are flush with the ends thereof. Aligned rectangular notches 151 and 152 are formed in the bracket, to snugly receive a bar 154 centrally apertured at 155 to form a bearing 70 for one portion of axle 138. From Figure 12 it

will be noted that this axle has also a lower bearing in an aperture 156. The axle itself is formed of a cylindrical central section having a reduced threaded lower end. The upper end of this axle has a cylindrical reduced section 157, followed by a squared section 158 and terminating in a reduced threaded portion 164. Upward movement of the axle is prevented by a pair of nuts 159 on the lower reduced end. A pulley or sleeve 160 fits the larger central section of axle 138 and is secured thereto as by a set screw 161, Figure 12. This pulley, in conjunction with nuts 159 acts to prevent axial movement of axle 138.

A spacing washer 162 is secured by bolts 163 to the central under side of wheel 139. The wheel and washer are formed with central aligned squared apertures fitting the squared portion 158 of axle 138. Thus when a nut on portion 164 is turned down, wheel 139 is fixed to axle 138. Base plate 144 rests upon the coplanar upper surfaces formed by sections 149 and 150 and is secured to these sections by cap screws 180 passing through holes 181 in their ends. Block 145 may be welded or bolted to shaft 137, Figure 12. Screws 182 are passed through plate 144 into this block. In this way, plate 144, shaft 137 and bracket 146 are secured together for movement as a unit about the axis of the shaft.

As shown upon Figures 11 and 12, flexible cables 46 and 47 pass through the open end of hollow shaft 137, thence through split bushings 165 and 166 received in holes in one leg of member 153. When nuts on the respective bushings are turned down, the sheathing of the cables 46 and 47 is clamped in position with respect to member 153. The cores of azimuth cables 46 and 47 are wrapped in respectively opposite directions about pulley 160 for one or more turns and the ends are secured thereto in any suitable manner, as by passing beneath the heads of screws, not shown. Thus when wheel 139 is turned, the cables act to correspondingly turn azimuth torque arm actuating lever 68 to cause azimuthal movement of the gun. The connections are such that clockwise movement of the wheel causes clockwise movement of the gun. It should be noted that the movement or displacements of the wheel 139, about the axes of axle 138 and shaft 137, determine the rates of movement of the gun and that for a given angular displacement of the wheel about a given axis, the gun (within the limits of its range of movement in elevation), will continue to rotate about its corresponding axis at a definite rate as long as that displacement of the wheel is maintained. Wheel 139 is provided with an adjustment knob 167 for convenience of operation.

A gear sector 168 is bolted to one leg of U-shaped member 153, in position concentric of the axis of tube or shaft 137. A fine adjustment shaft 169 having a knob 170 fixed to its end at the left side of strap section 132, is journaled in bearings, one of which is formed by holes in strap 132 and bar 133, and another by a hole in a lug 171, fixed to the upper surface of bar 133. The end of shaft 169 journaled in lug 171, is reduced to receive a spring 172 which acts between the shoulder formed by said reduced portion and an abutment 173, to urge shaft 169 outwardly and thus maintain a pinion 174 out of engagement with sector 168. Pinion 174 is fixed on shaft 169 and when it is desired to effect fine control of gun movement in elevation, knob 170 is grasped and pushed inwardly to mesh pinion 174 with sector 168.

Then by turning knob 170, very fine adjustments of the rate of movement of the gun in elevation may be effected. Upon release, spring 172 acts to automatically move pinion 174 out of mesh. It should be noted that, as best shown at Figure 14, strap 132 is formed with oppositely-disposed lugs 175 and 176 each positioned to engage the rim of base plate 144 when the wheel 139 is in respective extreme positions of adjustment. These lugs are so located as to permit a range of movement from a few degrees below the horizontal in the forward position of the wheel, to a substantially vertical rearward position thereof. The dimensions of the tube 137 and lever 68 are, of course, so correlated with arm 30 as to make the total permissible range of movement of the steering wheel about the axis of tube 137 exactly equal to the total permissible range of movement of arm 30 and pilot piston 11. In order to precisely coordinate these ranges of movement, each stop lug may be provided with an adjustable cap screw 177 and 178, Figure 14, so that the full effective range of rates afforded by the elevation oil gear may be utilized while avoiding the possibility of applying excessive stresses to the relatively delicate parts of the torque arm and pilot piston in their extreme limiting positions of movement.

From Figure 9, it will be noted that wheel 139 has an arcuate circumferentially-extending slot 179 formed therein and that a rack 184 is provided along one edge of this slot. A knob 182 is provided with a shaft 183, Figure 12, journaled in aligned bearing holes in plate 144 and block 145. A pinion 186 is fixed to shaft 183 and is normally held out of engagement with rack 184 by a coil spring 185 surrounding the shaft and acting between an abutment on the shaft and the bottom of a counterbore in block 145. When fine adjustments of wheel 139 are desired, knob 182 is pushed downwardly against the action of spring 185 to cause pinion 186 to mesh with rack 184. Turning of knob 182 then effects the desired adjustments.

A shaft 187 is journaled in lugs extending from the under side of base plate 144. From Figures 10 and 13 it will be seen that this shaft is substantially parallel to shaft 137 and that its ends are positioned slightly outwardly of the periphery of plate 144. Stop arms 188, only one of which is shown, Figure 10, are affixed to the respective ends of the shaft so that when these arms are in the position shown, their ends lie within the path of a pair of limit bolts 189 secured within holes or slots formed in the rim of disc 139. These bolts 189 and stop arms thus coact to limit the rotation of disc 139. The rotation is so coordinated with the azimuth oil gear as to coincide with the total range of movement of the pilot piston whereby the full range of azimuth rates may be utilized while, at the same time preventing the application of excessive forces to the oil gear when the limits of movements thereof have been reached. When desired for any reason, arms 188 may be pivoted downwardly out of the path of limit bolts 189. The arms are held in positions of pivotal adjustment by friction on shaft 187 afforded by a spring arm 190 engaging therewith and attached by a bolt 191 to the underside of plate 144.

Operation

When, for any reasons such as engagements at close range or inoperativeness of the director, it is desired to manually control the motors operating the gun in elevation and azimuth, the director 75 circuits are opened and slides 48 mounted upon

the elevation and azimuth oil gears are moved inwardly by thrusts applied to the exteriorly projecting portions 48a thereof. As previously described, this acts to cause spring arms 82 and 83 to embrace the respective torque arm pins 33.

The designated member of the gun crew or "tracker" then takes a position in seat 113 and grasps the steering wheel with the thumb and index finger of each hand while the three remaining fingers of each hand grasp the supports at 10 the respective sides of the steering wheel 139 to afford a steady influence. In the mid position of wheel 139 about the axis of tube 137, there will be no motion of the gun about its trunnion axis. Likewise in the mid position of wheel 139 about the axis of axle 138, there will be no azimuthal movement of the gun. Displacement of the wheel from these mid positions, in either direction will cause a movement of the gun in the corresponding direction and at a rate that is proportional to said displacement. When the tracers indicate that the trajectory substantially intersects the moving target, either or both knobs 170 and 182 may be grasped and pushed inwardly to engage their respective pinions whereupon turning of the knobs effects the desired final rate or rates of movement of the gun. Since the gun movements are in each case in the same direction as the movements of the wheel, and at a rate proportional to the displacements of the wheel from the aforesaid mid positions, the tracker obtains a sense of directly manually moving the gun and is thus enabled quickly to obtain the "feel" of the instrument and to effect smooth movements of the gun in the manner and through consecutive positions necessary to continuously and successfully engage the target. Under the conditions of use for which intended, therefore, the percentage of hits is increased over previous methods or systems while the time necessary to destroy or cripple the target is greatly reduced. When director firing is to be resumed, it is merely necessary to withdraw slides 48 to their outermost positions.

Modifications

Figure 15 shows a modification of the invention adapted for use in connection with a type of oil gear operating upon the same electrical principle described in connection with Figure 1. In this figure, 6' indicates a differential repeater operating in the same manner as 6, Figure 1, and having a torque arm 30' fixed upon its rotor shaft 29'. Arm 30' is connected at one end to operate a pilot valve 200 urged to central position, in which the gun is not moving about the corresponding axis, by a spring 201. It will be understood that movement of this valve by arm 30 in one direction or the other controls the admission of pressure fluid to one side or the other of a hydraulic motor as described in connection with Figure 1.

Arm 30' has its other end projecting so that the path of its tip intersects the flanges 203 and 204 of a limit spool or first slide 202 whereby the arm is limited in its range of movement. In the known type of oil gear as actually constructed, the aforesaid spool is adjustably mounted by a projection 205 apertured to slidably receive a projection 206 extending axially from spool 202. To adapt my invention to this oil gear, an axially and radially extending slot 207 is cut in spool 202 between the flanges thereof, to slidably receive a forked or second slide 208 having spaced, parallel arms 209 and 210 projecting forwardly into the path of the adjacent end of arm 30'. A single projection extends in the opposite direc-

tion from arms 209 and 210 and is apertured to receive with a smooth sliding fit, the straight shank of one arm of a bell crank 211 pivoted at 212 to a bracket 218 carried by the oil gear frame. The other arm of the bell crank is connected at 213 to one end of the core of a flexible Bowden cable 214. It will be noted that when bell crank 211 is in one position, its lower arm is parallel to the direction of sliding of spool 202.

The arms 209 and 210 are provided with springs, 215 which may be of the same form and arrangement as springs 82 and 83, previously described. Thus, when bell crank 211 is pivoted clockwise to the position shown at Figure 15, it acts to move 15 slide 208 toward arm 30' and cause springs 215 to embrace the end thereof. Then, when vertical movements of spool 202 are effected, corresponding pivotal movement is transmitted to arm 30' through the springs. These movements of spool 202 are produced by connection to one end of the core of a Bowden cable 216, as at 217. At their ends adjacent the oil gear, the sheathing of both cables may be secured in any suitable manner in bracket 218.

Means for operating cable 214 to move slide 208 by cable 214, and to operate cable 216 to manually control lever 30' when said slide is in the position shown at Figure 15, may be provided at any convenient station upon the gun. Such a station might be, for example, within easy reach of the member of the gun crew operating the steering wheel. At this station a slide or member 219 is mounted, as by means of a rectangular slot 220 and fixed guide member 221, for translation from 30 a first position to a second position shown at 35 Figure 15. A bell crank 222 is pivoted upon a fixed part 223 of the gun trunnion support and has a pin and slot connection 224 with slide 219. The other arm of the bell crank is connected at 40 225 to the adjacent end of the core of cable 214. The sheathing of the cable may conveniently be attached to a bracket 226 fixed on slide 219. Thus as slide 219 is moved from the aforesaid first to second position, bell crank 222 is pivoted thereby 45 to exert a pull on the core of cable 214, move bell crank 211 to the position shown upon Figure 15, and move slide 208 into operative engagement with arm 30'.

A rod 227 is slidably but non-rotatably mounted 50 within a bearing provided by a bracket 228. At its upper end, rod 227 is pivoted to a link 229, which, in turn, is slidably and pivotally mounted at 230 on a bracket 231. Brackets 228 and 231 are carried by the gun trunnion supports and hence train 55 with the gun about a normally vertical axis but do not move with the gun in elevation. Link 229 has a projection 232 to which a pair of springs 233 and 234 are connected. These springs act to urge the link 229 into the position shown, Figure 60 15. The adjacent end of the core of cable 216 is attached to link 229 as indicated at 235 so that the springs also act to urge spool 202 and rod 227 to the centralized positions shown upon the figure.

65 The lower end of rod 227 carries an offset roller 236, pivoted on an axis normal to the rod. The double-armed lever 68, leaf springs 82, 83, bracket 62 fixed to slide 219, and flexible cables 46, 47 extending from the steering or control disc to the 70 respective ends of lever 68, may all be identical with the identically-numbered parts of Figures 3 to 8, inclusive. For this reason it is deemed unnecessary to repeat the description thereof.

As previously stated, both elevation and azimuth slides 219 will usually be located within easy

reach of the crew member designated to control wheel 139. When shift from director to manual control is ordered, the aforesaid member grasps slide 219 and forces it to the position shown upon Figure 15. This movement acts to rock bell crank 222 and, through cable 214, bell crank 211. Slide 208 is moved to the left in its slot in spool 202 and springs 215 move over and embrace the end of lever 30'. At the same time lever 68 is moved with slide 219 so that springs 82 and 83 move over and embrace roller 236. Both elevation and azimuth slides are thus moved and all connections are thus effected whereby when control disc 139 is moved, a corresponding movement of lever 68 is produced. This movement acts through rod 227 and cable 216 to effect a vertical movement of spool 202 and slide 208 and thereby, a pivotal movement of torque arm 30'. Return to director control is effected merely by pulling slides 219 to the limit of their movement in the opposite direction. When this is done, spring 201 returns arm 30' to central or neutral position. Springs 233 and 234 return spool 202 to centralized position and the oil gear parts are then entirely free for director control through the differential repeaters.

Figures 16 to 19, inclusive, show a further modification adaptable to the type of oil gear shown upon Figure 15. In these figures, the oil gear parts are identified by the same numerals that are used in Figure 15 and need not be again described.

A special bracket 237 is adapted to be secured to the oil gear casing 238 to provide parallel projections 239 and 240. These projections have vertically aligned apertures within which a frame 241 is guided for reciprocation. This frame as shown at Figure 17, comprises vertical columns 246 and 247 connected at top and bottom by spacers 248 and 249. Column 246 has a pair of vertically-spaced, parallel apertures square in cross-section and extending transversely therethrough. Column 247 has a pair of reduced circular apertures, each in axial alignment with a respective aperture in column 246 to form guides for a pair of plungers 242 and 243 having inwardly bowed leaf springs 244 and 245 affixed to their ends, respectively.

From Figure 17 it will be noted that each plunger comprises a squared shank slidably fitting its aperture in column 246, and a reduced rod portion slidably fitting its aperture in column 247. The reduced rod portions terminate in heads 250 and 251. A plate 252 (see Fig. 18), has slots 253 and 254 extending inwardly from each end and of a width to receive the reduced shanks of plungers 242 and 243. This plate lies beneath the heads 250 and 251. A pull cord 255 has one end attached to plate 252 by an eye 256. The cord passes over a guide pulley 260, mounted on bracket 237, Figures 17 and 19, and carries a sleeve 258 slidably through an aperture in projection 239. Coil springs 257 and 258 surround the reduced portions of the plungers. At one end each spring engages against the shoulder formed between the two portions of the plunger while at its other end engages column 247. The two plungers are thus urged into a limiting outward or extended position wherein springs 244 and 245 engage and embrace the end of arm 30' between them so that, when in this position, reciprocation of frame 241 acts to pivot arm 30'. Retraction of the plungers from effective position is accomplished by a pull exerted on cord 255. This cord may extend to any convenient control station and may, if desired, be replaced by a Bowden cable or other known mechanical

or electrical control, for example, a solenoid carried by bracket 237 and acting upon a plunger or armature fixed to plate 252.

Spool 202 may be the same as shown in Figure 15, but since it is not used in the control being described, it is necessary to render its flanges 203 and 204 ineffective under conditions of manual control. This function is conveniently effected by cutting the flanges away along a chord thereof, as indicated at 259, Figure 19, for flange 204. The flanges are provided with aligned holes through which a rod 261 passes with a sliding fit. Rod 261 has its ends attached to the respective arms of a frame 262 having secured thereto a V-shaped projection 263 terminating in one section 264 of a hinge received between co-operating hinge sections 265 extending from one side edge of plate 252. See Fig. 18. A hinge pin passing through aligned holes in sections 264 and 265 acts to pivotally connect frame 262 to plate 252. As shown in Figure 19, when tension on cord 255 is released and springs 257 and 258 act to move the plungers forwardly into operating position, plate 252 and frame 262 are also moved forwardly. Rod 261 thus acts to rotate spool 202 to a position such that the flat, notched, or cut surfaces 259 of flanges 203 and 204, confront the end of arm 30' and the arm may be moved by movement of the frame 241, without interference from the flanges. Likewise when the plungers 242 and 243 are withdrawn by pulling on cord 255, the spool is rotated so that uncut portions of its flanges confront the edge of the arm 30' and act to limit its range of movement while at the same time rod 261 permits any desired vertical adjustments of the spool. Numerals 272 and 273, Figures 16 and 17, indicate the ends of flexible cables secured to frame 241 and extending to the steering or control wheel whereby, when the parts are in the positions shown in those figures, movement of the wheel about a corresponding axis, pivots arm 30' and initiates movement of the gun.

Since the range of movement of the gun in elevation is limited, usually to a little more than 90°, it is necessary in the case of the elevation oil gear, to provide means for stopping movement of the gun when it reaches the limit of its movement both in elevation and depression. Figure 17, shows one form which this means may have. A pulley 266 is journaled in bracket 237 and has a cord 267 extending thereabout and secured thereto at 268. One end of the cord is secured to head 250 and the other end is secured to head 251. A pinion 269 is attached to pulley 266 and is in mesh with a rack 270 slidably mounted in a vertical channel 271 provided by bracket.

A cord 274 has its ends secured to the ends of rack 270. This cord passes over pulleys 275 and 276 journaled on bracket 237 and thence over pulleys 277 and 278 journaled on a bracket 279 adjacent the elevating arc gear sector 108 of the gun breech casing. A lever 280 is pivoted on bracket 279 at 281 and has a roller 282 on its end lying in the path of elevation and depression stops 283 and 284, fixed to sector 108. Thus, when the gun reaches its elevation limit, for example, stop 283 engages and moves past roller 282 and pivots lever 280. Cord 274 then acts to move rack 270 downwardly and rotate pulley 266 counter-clockwise. The resulting pull on cord 267 withdraws plunger 243 and moves spring 245 out of contact with the arm 30'. As a result, arm 30' which had been raised by upward movement of frame 241 and plunger 243, is now free

to move downwardly to centralized position, which it does under the urge of spring 201. As a result, the gun stops.

The gun can then be moved downwardly only by reversing the movement of arm 30'. This requires that frame 241 be moved downwardly until spring 244 engages said arm. As soon as such engagement takes place, the gun starts to depress, stop 283 in moving past roller 282, returns lever 280 to the position shown and the resulting rotation of pulley 266 permits spring 258 to restore plunger 243 to its extended position. It will be understood that the force exerted by springs 257 and 258 when compressed, is not sufficient to overcome the friction of rack 270 and the pulleys about which cord 274 extends. If necessary, adjustable friction springs may be provided to press against rack 270. Sufficient slack may be provided in cord 267 to permit the vertical reciprocation of frame 241 and the plungers carried thereby. While the foregoing action has been described in connection with the elevation limit, stop 284 acts on lever 280 in the same manner to stop the gun when it reaches its limit of depression by causing retraction or withdrawal of plunger 242.

Guns of the type described usually have unlimited movement in azimuth and, in such cases, it is not necessary to provide the stop means just described for withdrawing plunger 242 and 243 individually. Hence these means will usually be omitted in the azimuth oil gear control. However, said means are adaptable to guns having limited movement in azimuth in which case lever 280 will be operated when the gun reaches its limits of azimuthal movement in each direction. The construction is therefore readily usable to limit the range of movement of the gun about both elevation and train axes.

I have thus provided a system that may be almost instantaneously placed into and out of action and, when in action, affords smooth, precise and accurate adjustments of the gun whereby the effectiveness of the gun is augmented and an increased number of enemy aircraft or other targets may be successfully engaged per gun during an encounter.

While I have shown the present preferred embodiment of my invention, alterations, substitutions and modifications will readily occur to those skilled in the art. The foregoing disclosure is therefore to be taken in an illustrative rather than a limiting sense. It is my intention to reserve all those changes, modifications and substitutions of equivalents that fall within the field and scope of the subjoined claims.

Having now fully disclosed the invention, what I claim and desire to secure by Letters Patent is:

1. In combination with a gun, a source of power for moving said gun, a movable torque arm for controlling said source, a slide, an operating lever pivoted on said slide and having means engaging said torque arm to move the same on pivotal movement of said lever, said slide being movable to free said torque arm of said engaging means.

2. In combination with a gun, a source of power for moving said gun, a movable element for controlling said source, a slide movable between a first and a second position, a lever pivoted on said slide, a pair of spring arms on said lever each arm being urged toward the other, said arms receiving said element between them when said slide is in said first position, and being entirely free of said element when said slide is in said second position, whereby pivotal movement

of said lever when said slide is in said first position, acts to control said source of power and thereby movement of said gun.

3. In a system for controlling a gun mounted for pivotal movement by a source of power and having a torque arm pivoted on an axis and connected to control said source of power, said torque arm having a pin eccentric of its pivot axis, said system comprising a slide mounted for translation between first and second positions adjacent said pin in a path normal to said axis, a lever pivoted on said slide, a pair of spring arms on said lever arranged to receive said pin between them when said slide is moved to said first position, and to be freed from said pin when moved to said second position, and manual control means operable from a remote station and effective to pivot said lever to thereby control said source of power when said slide is in first position.

4. In combination with a gun, by a source of power for pivoting said gun, a torque arm pivotally movable about an axis for controlling said source of power, a pin on said arm eccentric of said axis, a slide mounted for translation in a path normal to said axis adjacent said pin, a torque arm actuating lever pivoted on said slide, a pair of spring arms on said lever, said arms being bowed toward each other and, when said slide is translated to a first position, yieldingly receiving said pin between them, and when said slide is translated to a second position, being entirely freed from said pin, control cable means, extending from a remote control station and connected to pivot said lever, and a manually operable control element connected to actuate the end of said cable means at said station to thereby control said source of power and pivotal movement of said gun.

5. The combination as covered by claim 4, and releasable locking means effective to positively lock said slide in either of said first or said second positions.

6. In a manually-operable control system for a gun mounted for pivotal movement, a source of power for so moving said gun, a movable torque arm for controlling said source of power, an actuating pin on said arm, a clutch plate mounted for movement in a fixed path adjacent said pin, a lever pivoted on said plate, spring means on said lever positioned to yieldingly engage said pin when said plate is moved to a first position and to be free of said pin when said plate is moved to a second position and means operable from a remote control station and effective to pivot said lever to thereby control said source of power when said plate is in said first position only.

7. In a system for manually controlling a gun, a source of power connected to move said gun, a pivoted torque arm for controlling said source of power, a pin on said arm offset from the pivot axis thereof, a clutch plate mounted for movement adjacent said arm, a lever pivoted on said plate, a pair of confronting spring arms carried by said lever and receiving said pin between them when said plate is moved to a first position and to be free of said pin when said plate is moved to a second position, and control cable means mounted on said plate and connected to pivot said lever.

8. In a system for the manual control of a source of power connected to angularly move a gun, a torque arm pivoted on an axis for controlling said source of power, an actuating pin on said arm offset from said axis, a slide mounted for

translation adjacent and in a path normal to said axis, a double-armed lever pivoted on said slide, a pair of confronting spring arms carried by said lever, each spring arm extending substantially radially of the pivot axis of said lever and adapted to yieldingly receiving said pin between them when said slide is moved to a first position and to be free of said pin when said slide is in a second position, a bracket on said slide, and a pair of cable control elements carried by said bracket and having their ends connected to the ends of said lever, respectively.

9. In a system for the manual remote control of a gun, a source of power connected to train said gun, a pivoted torque arm for controlling said source of power, an operating pin on said arm eccentric of the pivot axis thereof, a casing enclosing said arm and pin, a slide mounted for translation within said casing in a path normal to, and adjacent, the axis of said arm, said arm having a portion extending exteriorly of said casing for manual translation thereof, a lever pivoted on said slide, spring means on said lever yieldingly engaging said pin when said slide is translated to a first position, the pivot axes of said arm and lever being substantially aligned when said slide is in said first position, and manually controlled means operative to pivot said lever from a remote control station.

10. In a gun control system including a torque arm pivoted on a first axis, an operating pin on said arm eccentric of said axis, said arm controlling a source of power angularly moving said gun, a clutch plate mounted adjacent said lever for translation normal to said axis, a torque arm actuating lever pivoted on said plate on a second axis parallel to said first axis, a pair of spring arms carried by said lever, each bowed toward the other from points remote of said second axis inwardly toward said axis, whereby, when said slide is translated to a position in which said axes are in substantial alignment, said spring arms embrace said pin between them for moving the same, irrespective of the position of said pin within its range of movement.

11. A gun control system including a torque arm pivoted on a first axis and having an operating pin eccentric of said axis, said arm controlling a source of power angularly moving said gun, a slide mounted adjacent said arm for movement in a direction normal to said axis, a double arm lever pivoted on said slide on a second axis, a pair of spring devices on said lever each extending radially of said second axis and embracing said pin between them when said slide is moved to a position to bring said axis into alignment, a bracket fixed on said slide, a pair of flexible control cables each having its sheathing fixed to said bracket and its core connected to a respective arm of said lever, said cables extending to a remote control station, and means at said station for manually operating said cables to thereby control said gun when said slide is in said position only.

12. In a system for control of oil gears each having a pivoted torque arm arranged to control a respective source of power for moving a gun in elevation and azimuth, means including flexible elevation and azimuth cables for effecting pivotal movement of said arms from a remote control station rotatable with said gun in train, a frame at said station, a hollow shaft journaled on said frame on an axis substantially parallel to the horizontal trunnion axis of said gun, an axle pivotally supported by said shaft for

5
10
15
20
25

rotation about an axis normal thereto, a manually controlled disc fixed to said axle, said elevation cable being connected with said shaft for actuation thereby and said azimuth cable being connected with said axle for actuation thereby.

13. A system for manual control of oil gears each said gear including a torque arm movable to control respective sources of power connected to move a gun about a normally vertical axis and a normally horizontal trunnion axis, elevation and azimuth flexible cable means, each said cable means being connected at one end to move a respective torque arm, said cable means extending to a frame carried by said gun for movement therewith about said vertical axis, a hollow shaft pivoted in said frame substantially parallel to the trunnion axis of said gun, an axle pivoted in said shaft on an axis normal to the axis of said shaft, said axle having a pulley portion, said elevation cable means having its core wrapped around and secured to said shaft for actuation by said shaft and said azimuth cable means having its core wrapped around and secured to said pulley portion for actuation by said portion.

14. In combination with a gun movable about a first normally vertical axis and a second normally horizontal trunnion axis, said gun having first and second power means connected to move said gun about said axes, respectively, a manually operable control disc, a frame carried by said gun for movement therewith about said normally vertical axis only, means mounting said disc on said frame for pivotal movement about a third axis parallel to the plane of said disc and said second axis, and about a fourth axis perpendicular to said third axis and the plane of said disc, first cable control means connected for operation by pivotal movement of said disc about said third axis and controlling said second power means, and second cable control means connected for operation by pivotal movement of said disc about said fourth axis and controlling said first power means.

15. In combination with a gun having first and second power means connected to move said gun about mutually normal elevation and train axes, respectively, a steering disc, a mounting frame for said disc movable with said gun about said train axis, means mounting said disc on said frame for pivotal movement about a first axis substantially parallel to said disc and said elevation axis and for pivotal movement about a second axis normal to said disc and said first axis, a control means for controlling the rates of operation of said first and second power means by and in proportion to the pivotal movements of said disc about said first and second axes, respectively.

16. In a system for the manual control of first and second power motors connected with a gun to move the same about elevation and train axes, respectively, valve means controlling said motors, a support bar mounted for movement with said gun in train only, a pair of parallel slides carried by said bar for adjustment thereon in a substantially horizontal first direction, a frame mounted on said slides for pivotal adjustment about a first substantially horizontal axis, a shaft journaled in said frame on a second axis parallel to said first axis, an axle carried by said shaft for rotation about a third axis perpendicular to said first and second axes, a steering member affixed to said axle, and first and second flexible shaft connections connected at one end to control

said valve means for said power motors, and at their other ends to said shaft and axle respectively.

17. In a control system for a gun mounted for angular movement, a source of power connected with said gun to move the same, a pivoted torque arm controlling said source of power, slide means mounted for translation between first and second positions, actuating means on said slide means adapted in said first position to embrace a portion of said arm eccentric of its pivot axis and to be out of contact with said arm in said second position, and means adapted to be operated from a remote station for moving said actuating means to thereby control said torque arm and gun.

18. In a control system for a gun angularly movable about an axis, power means connected to so move said gun, a movable torque arm controlling said power means, slide means mounted for translation between first and second positions, resilient actuating arms carried by said slide means and adapted to embrace a portion of said arm when said slide means is in said first position, and to be out of contact with said arm when said slide means is in said second position, and means manually operable from a remote station for moving said arms as a unit to thereby move said torque arm when said slide means is in said first position only.

19. In combination with an element movable to control a source of power turning a gun about an axis, a first slide mounted adjacent said element for translation in a first direction, a second slide mounted on said first slide and translatable thereon in a second direction normal to said first direction, between first and second positions, a pair of spring arms on said second slide adapted to operatively embrace said element when said second slide is in first position, and a single remote control means operable to shift said second slide between said positions and to translate said first slide to manually control said element when said second slide is in said first position only.

20. In a control system for a gun mounted for movement about an axis, power means connected with said gun for moving the same, an arm pivoted on an axis and connected to control said power means, a first slide mounted for translation in a first direction, a second slide mounted on said first slide for translation in a second direction between first and second positions, said axis and directions being mutually normal, means on said second slide adapted to operatively engage said arm when said second slide is in said first position, and remote control means operable to translate said first slide and thereby actuate said arm when said second slide is in said first position only.

21. In combination with a gun, a motor connected to angularly move said gun, a control arm pivotable about an axis to control said motor, a limit spool translatable in a first direction adjacent said arm, and having a guide slot axially and diametrically therethrough, a slide mounted in said slot for translation in a second direction between first and second positions, a pair of confronting leaf springs on said slide adapted to embrace said arm between them when said slide is in said first position, and to be clear of said arm when said slide is in said second position, a lever having a straight arm slidably connected to said slide and parallel to said first direction when said slide is in said first position, first and second flexible shafts connected to

translate said spool and lever, respectively, and extending to a remote station, a member at said station movable between first and second positions, control means carried by said member for operative connection to said first flexible shaft when said member is moved from first to second position, and means operated by the aforesaid movement of said member to actuate said second flexible shaft and thereby move said slide so that said springs embrace said arm.

5 22. In a control system for a gun arranged to be moved about an axis, power means for so moving said gun, an arm pivotable about an axis to control said power means, a frame mounted for sliding in a first direction adjacent said arm, a pair of plungers carried by said frame for movement in spaced parallel paths in a second direction, said axis and directions being mutually normal, and spring means on each said plunger and effective to embrace said arm between them when moved relatively to said frame from first to second positions, and means connected to slide said frame from a control station remote therefrom.

10 23. A control system for a gun movable about an axis, power means arranged to so move said gun, an arm movable in a plane for controlling said power means, a frame mounted adjacent said arm for translation in a first direction parallel to said plane, a pair of plungers mounted on said frame for translation in a second direction at an angle to said first direction between first and second positions, means carried by each plunger adapted to move into the path of said arm when both said plungers are moved to said first position, to thereby embrace said arm and effect control movement thereof or translation of said frame, and means responsive to movement of said gun at a limiting position about said axis to move the plunger effecting said movement, out of the path of said arm to thereby stop the gun.

15 24. A control system for a gun mounted for pivotal movement about an axis between limiting positions, power means for so moving said gun, an arm movable in a plane to control said power means, said system comprising a frame mounted adjacent said arm for movement parallel to said plane, a pair of plungers mounted on said frame for individual movement toward and from the path of said arm, means on said plungers arranged to embrace said arm when said plungers are in extended positions toward said path, spring means urging each plunger into its extended position, means responsive to movement of said gun into limiting positions to retract the plunger effecting said movement, and control means extending to a remote station and there operable to move said frame whereby manual control of said power means may be effected when said plungers are in extended position while movement of said gun is stopped when it reaches said limiting positions.

20 25. In a control system for a gun mounted for pivotal movement about an axis between limiting positions, a motor for so pivoting said gun, an arm pivotal about an axis to control said motor, a frame mounted adjacent said arm for movement in a direction at an angle to said axis, a pair of plungers movably mounted on said frame for movement toward and from the path of an eccentric portion of said arm, spring means urging each plunger individually into extended limiting position, means carried by said plungers to embrace said arm when said plungers are in said limiting position, means responsive to movement of said

gun into its said respective limiting positions to retract said plungers out of operative relation with said arm, and means operable to manually simultaneously retract said plungers out of operative relation with said arm.

26. In a control system for a gun pivotally movable about an axis by means of a hydraulic motor under the control of a torque arm pivotal about an axis, a frame mounted adjacent said arm for sliding in a first direction, a pair of plungers carried by said frame for movement thereon in a second direction between retracted and extended positions, said axis and directions being mutually normal, means carried by said plungers for resiliently embracing said arm when said plungers are in extended position only, means operable from a remote control station to control the movement of said plungers in unison between said positions, and to effect sliding of said frame to thereby pivot said arm when said plungers are in extended positions, and means responsive to movement of said gun to a limiting position, to retract that plunger causing said movement to thereby stop the gun in said position.

27. A control system for a gun, a power motor for moving said gun about an axis, and an arm controlling said motor, in combination, a spool and a frame reciprocably mounted adjacent said arm in parallel first directions, said spool having spaced flanges normally lying in the path of said arm to limit the range of movement thereof, said flanges having cut away portions aligned in said direction, a pair of plungers carried by said frame for movement in a second direction normal to said first direction, between retracted and extended positions, said plungers when in said extended position embracing and moving said arm in response to reciprocation of said frame, means on said frame operable to move said plungers to extended positions and simultaneously rotate said spool to move said cut away portions of said flanges opposite said arm whereby the path of said arm is free of said flanges.

28. In combination with a gun angularly mov-

able about train and elevation axes, two power sources, each connected to move said gun about a respective one of said axes, first and second movable elements each controlling a respective power source, a pair of slides, one mounted adjacent each element, each said slide being movable between first and second positions, resilient spring means carried by each slide and arranged, when its slide is in first position, to operatively engage its respective element and to be out of operative engagement with its element when its slide is in second position, a manually controlled part, means rotatable with said gun about said train axis only and mounting said part for movement about first and second mutually normal axes, the first one of which is substantially parallel to said gun elevation axis, a first operating connection responsive to movement of said part about the first of said mutually normal axes for moving said first element to thereby control the gun in elevation when its slide is in first position, and a second operating connection responsive to movement of said part about the second of said mutually normal axes for moving said second element to thereby control the gun in train when its slide is in first position.
